UNITED STATES PATENT OFFICE

161,155

VEHICLE TIRE

Aaron H. Benorden, Jesup, Iowa

Application February 11, 1949, Serial No. 799

Term of patent 3½ years

(Cl. D90—20)

To all whom it may concern:

Be it known that I, Aaron H. Benorden, a citizen of the United States, residing at Jesup, in the county of Buchanan and State of Iowa, have invented a new, original, and ornamental Design for a Vehicle Tire, of which the following is a specification, reference being had to the accompanying drawing, forming a part thereof.

Fig. 1 is fragmentary top plan view, and Fig. 2 is a cross-sectional view of a vehicle tire taken on the line 2—2 of Fig. 1, showing my new design.

I claim:

The ornamental design for a vehicle tire, substantially as shown.

AARON H. BENORDEN.
